UNITED STATES PATENT OFFICE

ERNEST A. LOWE, OF PLAINFIELD, NEW JERSEY, ASSIGNOR TO AUTOMATIC SPRINKLER COMPANY OF AMERICA, OF CLEVELAND, OHIO, A CORPORATION OF DELAWARE

AUTOMATIC AND MANUAL REMOTE CONTROL FIRE EXTINGUISHING SYSTEM

Application filed November 11, 1925. Serial No. 68,283.

This invention relates to the art of fire extinguishing apparatus and is particularly applicable to the automatic dry-pipe system in which the fire extinguishing fluid is supplied to any of a number of protected fire sections or areas whenever a fire condition occurs in such section or area.

It is one of the primary objects of the invention to provide co-acting controls for the main supply pipe line and for the branch lines leading to the different sections so that on the occurrence of a fire condition in any section the water or other fire extinguishing fluid will be discharged in that section alone thereby concentrating the water supply in the fire area and increasing the effectiveness of the same and also avoiding flooding an area in which no fire has occurred.

It is a further object to provide an apparatus of this type which will be rapid and unfailing in its operation and which responds readily and automatically to flood an area where a fire condition exists.

It is another object to avoid the necessity of constant attention to the system by having all of the parts thereof normally neutral or in a state of rest but with sufficient latent power stored in the controlling mechanism to operate the controls instantly when necessity arises.

The invention contemplates further to provide for easily draining the pipe lines after the apparatus has been used and to allow air to circulate within the interior of the pipes to maintain them in a dry condition.

The system herein disclosed possesses important advantages over those previous dry-pipe systems in which air pressure is maintained by compressors in the water distributing system and in which the main or master valve is held normally closed by such pressure until by a relief of pressure caused to take place in the fire area by a suitable control device, a relief of the pressure at the main or master valve is caused to take place whereby said master valve is caused to open thus allowing the water to pass into the distributing pipe to be conducted thereby to the fire areas and there ejected. In this system valuable time is lost before the

pressure of the water flowing in the distributing system can force out the volume of air so as to be able to reach the sprinkler head or other outlet. Furthermore, as will be obvious, an air leak in the system may bring about a flooding of the distributing pipes and consequent damage through escape of the water at the point of leak or at other points where there is a normally free outlet for escape thereof. Also said system requires the use of air compressors and motors therefor to maintain a predetermined minimum air pressure suitable for the intended operation.

A further advantage of my system over that just referred to is that I avoid the difficulties due to the presence of moisture resulting from the cooling of the air after the compression and the consequently liability to the formation of ice in the pipes of the system, thus clogging the same.

In the modified form of dry system in which the main distributing pipe is kept at atmospheric pressure and a supplemental control pipe is used for effecting the remote control of the main valve by relief of pressure in said supplemental pipe, the same objections are present, namely the liability or possibility of the premature opening of the main valve by a leakage in the control pipe and the same necessity for use of an air compressor and motor together with expensive upkeep of the same. The disadvantages of both said dry-pipe systems in the respects described are entirely overcome by my improved dry system in which there is no danger of premature operation from a leak of the air, no necessity for employing compressors or motors and no impairment of prompt operation through delay ensuing in the previous systems either from the slow escape of the air under pressure in the main distributing pipe or in the remote control supplemental pipe or conductor.

Other advantages will be obvious to those skilled in the art and need not be here enlarged upon.

Other and more specific objects will appear as the description proceeds.

In the drawings,

Fig. 1 represents more or less diagrammatically one embodiment of the invention as applied to a complete fire extinguishing system.

5 Fig. 2 is a sectional view of one type of supply valve which may be employed.

Fig. 3 is a sectional view of the subject-matter shown in Fig. 2 with the valve moved to open position.

10 Fig. 4 is a sectional view of one type of control for use at the discharge outlet of a pipe line.

Fig. 5 is a similar view showing the position the parts assume when operated.

15 Fig. 6 is a sectional view of a manually controlled valve for automatically operating the main control valve.

Fig. 7 is a sectional view through a type of differential control valve which may be 20 employed in the system if desired.

Fig. 8 is an elevational view of an independent manual control for a remote valve.

25 Fig. 9 illustrates a modification of the system as applied to a plurality of fire sections or areas.

Fig. 10 is a sectional detail view of the type of secondary valves shown in Fig. 9; and

Fig. 11 is a similar detail view of the main valve shown in Fig. 9.

30 Referring now to the details of the drawings there is disclosed in Fig. 1 the first form of my invention as applied to a plurality of fire sections. The main water supply pipe is indicated at 12 and connects with any desired 35 number of risers or feed mains 14 (one such riser being shown in Fig. 1) leading away from the main valve head 15. It is preferred to provide a manual control valve 16 so that the supply of fire extinguishing fluid, 40 water for example, may be manually shut off when desired, as during resetting of apparatus. For the sake of safety the pressure gauge indicated at 17 may likewise be installed on the water main adjacent its connection at the head 15 to indicate the available water pressure. From the risers 14 the required number of branch lines 18 and 19 extend into the different fire areas to insure 45 a supply of water to all parts of the structure 50 protected by the system.

In order to maintain the pipe lines including the risers and branch lines normally dry and subjected to atmospheric pressure, I have employed a main control valve within the 55 head 15 constructed for automatic operation and positioned in any desired location, where it may be protected from the cold or other harmful influences. The risers and branch lines may therefore be installed in any unheated building without danger of the pipe becoming frozen in extreme weather. In order to concentrate the supply of water in the location where a fire had occurred the branch lines leading to the various fire sections are normally maintained closed by the

valves or other closures 20 and 21 hereafter being referred to as secondary valves and being positioned adjacent the discharge outlets of the branch lines.

70 The main valve 15 and any desired number of secondary valves or closures 20 are constructed to be automatically operated upon the occurrence of a fire condition, the secondary valves responding only to local influences in the particular fire section where they 75 are positioned. To this end I have shown a separate impulse conducting conduit 22 extending from the main control valve 15 and connected with branch conduits 23 and 24 which branch conduits lead to the various fire 80 sections or areas. The conduits 22, 23 and 24 are formed of tubing and are normally subjected to atmospheric pressure by providing a restricted leak or impedance 33 which is sufficiently large to maintain the interior of 85 the conduit at substantially atmospheric pressure but which is ineffective to relieve the pneumatic impulse utilized for operating the valve 15 as hereinafter fully described. Positioned at various points along the branch 90 conduits 23 and 24 and branch lines 18, 19 are a number of temperature responsive mechanisms for opening the secondary valves and creating an impulse within the conduits 95 22, 23 and 24 to operate the main control valve 100 upon the occurrence of a fire condition in the fire sections where such temperature responsive devices are located. The preferred forms of impulse creating and impulse receiving mechanisms are fully described below.

105 The main control valve 15 is constructed as shown in detail in Figs. 2 and 3. The valve casing includes the water inlet 25 and outlet 26 the former being connected to the water main 12 and the latter to the risers 14. Positioned between the inlet and outlet is an opening 27 which accommodates the operating support 28 for the valve closure 29. This closure is constructed to control the inlet 25 and also the opening 27 so that when the closure is moved away from the valve seat 30 of the inlet it is moved into engagement with the valve seat 31 of the opening 27 to close the interior of the head 15 and to 110 permit the passage of water from the water main to the risers. This position of the valve closure is shown in Fig. 3. The opening 27 serves a further important function of permitting the system to be automatically 115 drained when the main valve is closed and also of permitting the circulation of air within the supply pipes extending to and into the fire areas. The support 28 for the valve is shown as pivoted at 32 to a supporting structure 34 positioned without the valve casing 120 125 125.

The valve member 29 is constructed to be controlled by an impulse preferably pneumatically transmitted through the conduits 130

23 or 24 and 22. In the form of the invention disclosed the pneumatic impulse is utilized to expand a partially collapsed bellows 36 to move the operating element 38 thereof outwardly. In order to insure instant and unfailing operation of the valve controlling mechanism it is preferred to store a considerable quantity of latent mechanical or other energy in the valve controlling mechanism 5 outwardly. In order to insure instant and unfailing operation of the valve controlling mechanism it is preferred to store a considerable quantity of latent mechanical or other energy in the valve controlling mechanism 10 which energy can be easily released to open the valve. To this end the valve controlling mechanism includes a weighted lever 40 pivotally supported as at 41 and which is normally retained in raised position (but in a 15 condition of unstable equilibrium) by means of a detent or latch 42. The latch 42 has one end 43 thereof engaged against the weighted lever 40 and the other end 44 positioned to be engaged by the movable element 38 of the 20 bellows 36. The locking lever 46, shown as pivotally supported at 47 on the supporting structure 34, includes a locking lug 48 and an operating extension 50. The extension 50 is positioned to be engaged by the weight- 25 ed portion of the lever 40 when the latter swings downwardly due to the force of gravity. A valve control lever 52 is pivotally supported from the valve head as by means of the bracket 53 and includes a locking ex- 30 tension 54 constructed to engage the lug 48 and an adjustable set screw or stop member 56 which engages the operating rod 28 of the valve to hold the latter normally in closed position against the valve seat 30. The ad- 35 justable stop member 56 permits the valve closure 29 to be accurately closed when the lugs 48 and 54 are in engagement.

By this construction it will be seen that upon a pneumatic impulse being transmitted 40 through a conduit 22, 23 or 24 to the bellows 36 the member 38 is moved against one arm 44 of the latch 42 to release the weighted lever 40 which thereupon falls by gravity against the operating extension 50 of the re- 45 taining lever 46 releasing the latter from en- gagement with the control lever 52, thereby permitting the valve closure 29 to move from closed to open position, that is, from the valve seat 30 to the valve seat 31 to permit 50 the passage of the fire extinguishing fluid from the water mains toward the discharge outlets.

Referring now to the preferred form of mechanism for creating the valve operating 55 impulse, there is shown in Fig. 4 one form of automatically controlled combined discharge outlet and impulse creating mechanism which may be employed. This mechanism includes a collapsible bellows 58 normally 60 held in expanded position by means of the toggle levers 60 having one pair of arms thereof engaging above and below the bellows, the other ends, herein termed the jaws, being normally held spaced by means of the 65 co-acting levers 62 which engage against one

another and against the interior of the jaws 61. The levers 62 are normally prevented from separating to permit the collapse of the bellows 58 by a temperature responsive structure shown as a fusible element 64 connect- 70 ing the outer or free ends of the levers 62. According to this form of the invention the discharge outlets 63 of the branch lines 19a are normally closed by means of the dis- 75 placeable closures 65 held in place by the levers 62 coincidently with the spreading of the lever 60. The jaws 61 of levers 60 are positioned between the closure 65 and the adjustable set screw 67 carried by the sprinkler head 63a. The spring member 66 shown as positioned within the bellows 58 is normally under tension and when the levers 62 and 60 are released by reason of fusion of the element 64 or otherwise the bellows is collapsed by means of the spring 66 permit- 80 ting the displacement of the closure 65 and creating the pneumatic impulse in the con- duct 24 required for operation of the bellows 36 and valve mechanism 15. The position of the parts upon a release of the levers 62 as by reason of the element 64 being fused 85 upon the occurrence of a fire condition is shown in Fig. 5. The fluid discharged from the outlet 63 may be caused to assume the form of a spray by means of any preferred 90 form of sprinkler head 63a.

Fig. 6 shows another type of operator which combines the manual and automatic control for the water supply. According to this form of the invention the branch line 106 or 19b is normally closed by means of the movable valve closure 68 which may be held against the valve seat 69 by means of the hand lever 70 and screw-threaded shank 71. The shank 71 carries abutment members 72 positioned to engage above and below one end of the lever 74 so that as the shank is screwed upwardly the lever is rocked on its pivot. The lever 74 includes the operating head 76 positioned to engage the normally 100 expanded bellows 78 utilized to create the valve operating impulse in the conduit 23. The bellows 78 is normally held in expanded position by means of a relatively small ex- 105 pansion spring 79. It is considered desirable to store a certain supply of power in the arm 83 so that it will be unfailing in operating the bellows 78. To this end there is disclosed a snap spring construction including a rela- 110 tively strong spring 80 one end of which is supported from the collar 81 rotatably mounted upon the shank 71, the other end of the spring being connected to the free end of the arm 82 keyed for rotative movement 115 with the lever 74 the arm 82 being placed beyond a side edge of the valve housing to permit its rotative movements. By means of this construction it will be seen that upon the valve closure 68 being manually moved 120 a certain distance away from the valve seat 125

69 the control arm 74 will be rocked counter-clockwise beyond the center with relation to the spring 80 which spring will exert a snap action causing the head 76 to engage the bellows 78 to create the impulse in the conduit 23 necessary to open the main control valve 15. This type of control is particularly useful with a manually manipulated fire extinguishing apparatus, for example the hose 106, although it may be used with the discharge apparatus 19b shown in Fig. 1.

In Fig. 7 I have shown a type of differential valve for controlling either the main or branch lines. According to this construction the valve head 85 includes the water inlet 86 normally closed with respect to the water outlet 88 by means of the valve closure 89 and valve seat 87. The valve closure 89 is constructed to be maintained in closed position by means of the water pressure in the inlet 86. To this end a relatively large supplemental valve closure 90 is constructed to be moved with the closure 89 and to seat against the valve seat 91 when the closure 89 is in closed position. The valve head 85 includes a restricted passage or bypass 92 around the valve closure 89 and leading from the inlet 86 to the differential chamber 94 to create a force on the back side of the valve head 90 greater than the force on the face of the relatively smaller valve closure 89 thereby maintaining the valve closure 89 normally in engagement with the valve seat 87. This valve mechanism is controlled similarly to that described above in that a pneumatic impulse produced by any of the devices disclosed herein and transmitted through the conduit 22a causes the valve 89 to be opened and to be retained open until manually released and reset. To this end the bellows 96 which is normally maintained in partially collapsed condition by spring or other means is operatively associated with a detent 98 which in turn engages beneath a weighted lever 99 to retain the latter in raised position. The outlet from the chamber 94 is controlled by means of a spring-pressed compressible mechanism 100 the movable portion of which carries an operating rod 101 terminating in the valve head 102. The valve head 102 when in raised position engages against the valve seat 103 of the escape outlet 104 leading from the interior of the chamber 94 to the discharge outlet 105 thus maintaining the pressure in chamber 94 and retaining the valve 89 closed. The member 100 may be depressed and retained in that position by means of the weighted lever 99 upon the occurrence of an expanding impulse in the bellows 96. The restricted passage 92 being smaller than the escape passage 102 the escape of pressure from chamber 94 reduces the differential pressure on valve clapper 90 and the water pressure is permitted to open valve 89 thus pro-

ducing a flow of water to the fluid distributing pipes.

In Fig. 8 there is shown a simple type of manual control so that the main supply valve may be operated independently of any of the above controls. The construction includes a lever 108 pivoted at 109 to an extension of the conduit support 110. The lever is connected as at 111 to a movable portion of the bellows 112 and terminates in an operating handle 114. It will be obvious that by this means the bellows 112 may be manually compressed to create an impulse in the conduit 23 to operate the control valve, for example, that shown at 15 in Fig. 1.

According to the above described construction it will be seen that there are provided a series of fire extinguishing pipes normally maintained closed adjacent the source of fluid supply and also at points adjacent the discharge outlets. Upon the occurrence of a fire condition the temperature responsive control mechanism operates to open the discharge outlet and simultaneously to open the main control valve permitting the fire extinguishing fluid to enter the pipe lines and to pass from the discharge outlets. If desired the discharge outlets and main valve may be manually controlled or if preferred the main valve may be manually controlled from a position remote therefrom and the discharge outlets controlled as by means of any usual type of manual or automatic valve.

Under certain conditions as where the source of water supply is relatively remote from the protected fire sections or areas, it is preferred to have the impulse created in the fire section operate the secondary or supplemental valves only and to create anew at the supplemental valves the impulse for opening the main control valve. In this way any desired number of main and control valves may be used without danger of failure of the impulse to operate the various valves necessary to permit discharge of the water.

This apparatus is constructed as shown in Figs. 9, 10 and 11.

In Fig. 9 there is disclosed a fire extinguishing system shown as applied to a building having a plurality of floors which may require any number of branch lines and discharge outlets. In this figure the water main indicated at 12a is normally closed by means of the main control valve 15a. The feed mains 14a lead to the protected portions of the building and terminate in the branch lines, a sufficient number of which are provided to adequately protect the same against fire. It is preferred to close all of the branch lines with respect to the feed mains so that upon the occurrence of a fire condition in any one location the pipe lines in that location only will be supplied with fire extinguishing fluid. To this end a plurality of secondary control valves 116 are positioned between the 130

feed mains and the discharge outlets of the branch lines. The valves 116 are controlled by means of the temperature responsive impulse creating mechanism 118 similar, for example, to that shown in Fig. 4, but with or without the displaceable closures 65 shown in that figure as the valves 116 avoid the necessity in many installations for the closures 65. This impulse creating mechanism includes a normally expanded bellows formed with a tensioned spring or weight tending when released to collapse the bellows to create an impulse in the conducting conduit to operate the valve. The impulse creating bellows will normally be held in expanded condition by means of fusible elements as shown in Fig. 4 so that upon the occurrence of a fire condition the element is fused and the bellows collapsed to create the impulse which moves forward to operate the corresponding valve 116. The impulses from the mechanisms 118 to the valves 116 are carried through the conduits 119 and operate the bellows 120 to control the valve as described below.

The control elements of the valve 116 are substantially identical with the impulse operated valve shown in Figs. 2 and 3 except that means is provided for relaying the impulse from the valve 116 through the conduit 122 to the main valve. This may be accomplished by placing a normally expanded bellows 124 in position to be contracted by means of the weighted lever 40a when the latter is released to open the valve 116. By this construction it will be seen that a new impulse for operating the main valve is created substantially simultaneously with the opening of a secondary or supplemental valve 116 and that the power stored in the weighted lever 40a insures a relay of the impulse to the main valve 15a.

In Fig. 9 there is shown a second series of branch lines 126 connected to directly operate the main control valve 15a. The temperature responsive mechanisms 128 shown in this figure may, for example, be constructed as shown in Figs. 4 and 5 or they may be manually controlled as in the form of the invention shown in Fig. 6.

The main control valve 15a is shown in Fig. 11 and is identical in construction with that shown in Figs. 2, 3 and 10 except that means is provided for controlling the valve operating weighted lever 40b either from the impulse relayed through the conduit 122 or from the impulse conveyed through the conduit 129. The impulse conveyed through the conduit 122 operates to expand the bellows 130 which operates on lever 42b to free the weighted lever 40b while that conveyed through the conduit 129 expands bellows 132 to depress an extended end of the latch 42b. The mechanism disclosed in Fig. 11 illustrates the fact that a plurality of separate impulse conducting conduits may extend to the

said main control valve to release the fire extinguishing fluid into the distributing pipes. The number of such conduits may obviously be multiplied as desired.

According to the above described construction there is provided a complete fire extinguishing system wherein the fire extinguishing fluid is made available to extinguish a fire in any of a number of fire sections or areas but in which the fluid is automatically supplied only to such area or areas as are actually subjected to a fire condition. The controlling mechanism for the main and supplemental valve closures is normally in a state of rest but each of the operating mechanisms is provided with a supply of latent energy which is easily released and which operates uniformly to admit the fluid supply. It is obvious that other forms of latent energy, as well as releasing and conducting mechanism may be employed without departing from the spirit of the invention.

The fluid supply may have any number of automatic and manual controls which may be operated without influencing any of the other controls. The relay type of control disclosed in Figs. 9, 10 and 11 assures a sufficiently strong impulse to be transmitted to the main valve to operate the same. If the main valve is to be placed a great distance from the secondary valves or if the secondary valves are placed a great distance away from the automatic impulse creating mechanism located in the fire section, it is obvious that additional impulse transmitting relays may be installed at any desired point or points along the conduits 22, 23, 24, 119, 122, etc.

The main control valve may accordingly be located any desired distance from the fire areas and may be placed where the water pipe will not be subjected to freezing conditions. Since the supply pipes for the fire areas are normally dry they may be placed in unheated buildings without danger of the water freezing therein.

Furthermore since both the water pipes and the impulse conducting conduits are normally subjected to atmospheric conditions the system responds quickly and without the necessity of relieving any additional pressure from the pipe lines. This feature also avoids the necessity of constant upkeep expense for compressors etc. and avoids the possibility of the water being prematurely admitted to the pipe lines through failure of the restraining pressure usually employed.

From the foregoing it will be obvious that in the case of air or other fluid control the system operates essentially by producing a difference of pressure or tension in the air pipe and that instead of acting by increase the devices might be actuated through decrease of the normal pressure in the controlled pipe. In other words, instead of

working the system by plenum as described it might operate by exhaust or vacuum.

While I have shown certain specific forms of my invention it is to be understood that 5 these are merely illustrative of the invention, the scope of which is to be ascertained from the appended claims.

What I claim as my invention is:—

1. In a dry-pipe fire extinguishing system, 10 a source of fire extinguishing fluid, control mechanism therefor, means for conducting said fluid to a fire section, means for transmitting control impulses from said fire section to said control mechanism, and means 15 comprising a contractible chamber and means for contracting the same for creating a relatively sudden pneumatic impulse in said transmitting means to operate said control mechanism.
2. A fire extinguishing apparatus including a supply pipe, control mechanism for controlling the admission of fire extinguishing fluid to said pipe and including a control valve, means for controlling said control 25 mechanism, and including a pressure responsive device operatively associated with said valve, a pressure producing device in a fire area and a pneumatically controlled pressure 30 relaying mechanism intermediate said pressure responsive and pressure producing devices for building up and transmitting a renewed pressure to said pressure responsive device, and conduits for conveying pressures from said pressure producing device to said 35 relaying mechanism and from said relaying mechanism to said pressure responsive device.
3. In a dry-pipe fire extinguishing system, the combination of a supply pipe normally 40 dry, a pneumatically controlled valve controlling the admission of the fire extinguishing fluid to said supply pipe, branch pipes from said supply pipe, each having a secondary control valve normally closed, pneumatically controlled means for causing said 45 secondary valve to open and means operated by the secondary control valve mechanism for transmitting a pneumatic impulse to the main valve to cause the latter to open when 50 the secondary valve is opened.
4. In a dry-pipe fire extinguishing system, a main supply pipe, branch pipes extending from said main pipe to a plurality of fire sections, a main valve for said main supply 55 pipe and secondary valves for said branch pipes, means responsive to pneumatic impulses for operating said valves, temperature responsive means for creating a pneumatic impulse to operate a secondary valve, and 60 means controlled by said temperature responsive means for creating a pneumatic impulse to operate said main valve.
5. In a dry-pipe fire extinguishing system, a main supply pipe, branch pipes extending 65 from said main pipe to a plurality of fire sec-

tions, a main valve for said main supply pipe and secondary valves for said branch pipes, means responsive to pneumatic impulses for operating said valves, temperature responsive means for creating a pneumatic impulse to operate said secondary valves, means controlled by said temperature responsive means for creating a pneumatic impulse to operate said main valve and independently acting temperature responsive means for operating 75 said main valve.

6. In a fire extinguishing system, a source of fire extinguishing fluid, means for conducting said fluid to a fire area, a valve for controlling said fluid, pneumatically controlled mechanism for actuating said valve, mechanical devices in communication with said mechanism for creating a pneumatic impulse, normally inactive means for actuating said impulse creating devices and temperature responsive means for rendering said 80 last named means active.

7. In a dry-pipe fire extinguishing system, the combination with a main valve normally closed, a supplemental air conduit containing air at atmospheric pressure and extending from the main valve to a fire area and provided with means for compensating for atmospheric changes of temperature to maintain an interior pressure at all times which is substantially that of the atmosphere, a collapsible element at the fire area capable of being collapsed and producing a pneumatic impulse in said conduit and means at the main valve, responsive to said pneumatic impulse, for producing a hammer blow at said main valve for causing the same to be opened. 90

8. In a dry-pipe fire extinguishing system, the combination with a control valve for admitting a fire extinguishing fluid to said pipes, of a supplemental control conduit containing air at atmospheric pressure and extending from the main valve to the fire area, said conduit being provided with means for compensating for changes in pressure due to 105 changes of temperature of the surrounding air, a bellows device connected to said conduit and normally expanded, means at the fire area for causing said bellows to suddenly contract, means for normally holding the 110 control valve closed, mechanism for releasing said valve and a pneumatically actuated expansible device connected to the supplemental conduit at the control valve for supplying force for actuating said releasing mechanism and responsive to the pneumatic impulse produced by the contraction of the bellows device in the fire area. 115

9. In a fire extinguishing system, a fluid supply pipe containing air at atmospheric pressure, a fluid supply valve therefor, a remote control for said valve, said control including an impulse creating mechanism and an impulse conducting conduit, said impulse creating mechanism comprising a detent con- 125

- trolled, normally dormant or uncharged, power supply apparatus, and temperature responsive means to release said detent for the purpose of creating said impulse.
- 5 10. In a fire extinguishing system, a fluid supply pipe, a fluid supply valve therefor, a remote control for said valve, said control including a pneumatic impulse creating mechanism and a pneumatic impulse conducting conduit operatively associated therewith and with said valve, said mechanism comprising a supply of stored mechanical power, and a releasable detent for releasably restraining said mechanical power.
- 10 15. 11. In a device of the character described, including a supply pipe, a closure for said pipe, means for normally retaining said closure in closed position with respect to said pipe, temperature responsive means for releasing said closure and means including a supply of latent energy for creating a pneumatic impulse upon the release of said closure.
- 20 25. 12. In a fire extinguishing system including a supply pipe, a distributing pipe and an impulse conducting conduit, a valve for controlling the supply of fluid in said distributing pipe, means including manually operated mechanism for opening said valve, a main valve for said supply pipe operatively associated with said conduit to produce a flow of the fire extinguishing medium to said first named valve, and means operative upon the opening of said first named valve for creating an impulse in said conduit to operate said main valve.
- 30 35. 13. In a fire extinguisher, release mechanism therefor, pneumatically operated means for actuating said release mechanism and a pneumatic pressure producing device pneumatically connected therewith and comprising a spring-actuated detent-controlled collapsible container and means responsive to temperature increase in a fire zone controlling said detent.
- 40 45. 14. In a fire extinguishing system, means for supplying a fire extinguishing fluid under pressure to said system, release mechanism for said supply means and operated by a pneumatic impulse, distributing piping for conveying said fire extinguishing medium to a fire zone normally maintained dry and at substantially atmospheric pressure, a normally closed outlet therefor, and heat-responsive means for opening said outlet and coincidentally creating a pneumatic impulse for releasing said release mechanism.
- 50 55. 15. A fire extinguisher operating device including pressure responsive release mechanism, air compressing means, means to normally maintain said air compressing means inactive, means to conduct compressed air from the compressing means to said pressure responsive release mechanism, and temperature responsive means to render active the
- said means which retains the air compressing means inactive.
- 60 65. 16. In a fire extinguishing system for a plurality of fire zones, a source of supply for fire extinguishing fluid, distributing pipes for distributing said fluid to the various fire zones, means for controlling the admission of fluid from said source of supply to said pipes, actuating means for said controlling means and including a plurality of units each formed with a pressure producing device and a pressure responsive device and supplemental tubing connecting said devices, the pressure responsive devices of each of said units including an element actuated by said pressure responsive device and independently of the other pressure responsive devices for actuating said controlling means.
- 70 75. 17. In a fire extinguishing system for a plurality of fire zones, a source of fire extinguishing fluid supply, distributing piping for conducting said fluid to the various zones, outlets for said piping in said fire zones, a main control mechanism for said fluid supply including a release lever, a plurality of control units, each unit comprising a temperature responsive element in a fire zone and a releasing element controlled thereby and positioned to engage and release said release lever, means actuated thereby for operating said control mechanism, each of said units operating independently to engage and release the release lever of said main control mechanism.
- 80 85. 18. In fire extinguishing system for a plurality of fire zones, a source of supply for fire extinguishing fluid, distributing pipes for distributing said fluid to said zones, a main valve for controlling the admission of fluid from said source of supply to said pipes, temperature responsive mechanism for releasing said main valve, said mechanism including a plurality of units each formed with a heat responsive pneumatic impulse producing element in a fire zone and an impulse responsive element and supplemental tubing connecting said elements and means responsive to the actuation of the pneumatic impulse responsive element of any of said units for opening said main valve.
